(57) **CLAIM**

The ornamental design for a head mounted display with transitional graphical user interface set, as shown and described.

DESCRIPTION

FIG. 1 is a perspective view of the front, top and left side of a head mounted display with transitional graphical user interface set showing our new design;

FIG. 2 is a perspective view of the rear, bottom and left side thereof with a set of the fifth image of the transitional sequence displayed on the screens;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front view of a single display screen of the set, showing the first image in the sequence;

FIG. 10 is a front view of the single display screen thereof, showing the second image in the sequence;

FIG. 11 is a front view of the single display screen thereof, showing the third image in the sequence;

FIG. 12 is a front view of the single display screen thereof, showing the fourth image in the sequence;

FIG. 13 is a front view of the single display screen thereof, showing the fifth image in the sequence;

FIG. 14 is a front view of the single display screen thereof, showing the sixth image in the sequence;

FIG. 15 is a front view of the single display screen thereof, showing the seventh image in the sequence;

FIG. 16 is a front view of the single display screen thereof, showing the eighth image in the sequence; and,

FIG. 17 is a front view of the single display screen thereof, showing the ninth image in the sequence.

The broken lines shown in the drawings are for the purpose of illustrating environmental structure and form no part of the claimed design.

The appearance of the transitional image sequentially transitions between the images shown in FIGS. 9 through 17. The process or period in which one image transitions to another image forms no part of the claimed design.

1 Claim, 16 Drawing Sheets
